JOSEPH O. CADIEUX, OF MERIDEN, CONNECTICUT, ASSIGNOR TO CONNECTICUT TELEPHONE & ELECTRIC CORPORATION, OF MERIDEN, CONNECTICUT, A CORPORATION OF DELAWARE

ELECTRIC TERMINAL CONNECTER

Application filed April 22, 1931. Serial No. 531,970.

My invention relates particularly to devices for detachably connecting the end of a cable to a spark plug. Such constructions especially when used in connection with airplane motors 5 are subjected to extreme vibration and other stresses and yet are required to maintain a perfect connection under all circumstances. In many constructions it is necessary to shield the spark plug such for instance as for 10 the purpose of protecting against radio interference.

The object of my invention is to provide means of connection which will answer the foregoing purposes. I have specifically 15 sought to provide a construction which can be used to connect a cable to a spark plug having a metallic shield.

One object is to provide a construction which can be utilized with spark plugs of different lengths.

Another object is to protect the spark plugs from the dripping of oil or other foreign substances.

Another object is to provide a simple but 25 rugged terminal clip which can be readily handled and which can be relied upon.

In carrying out the invention I provide a body which serves to receive the end of the cable and by which it can be handled and secured to a shield. To the extreme end of this 30 body I secure a suitable form of clip for engaging the spark plug tip.

The terminal body is formed of a metallic tubular member and an insulating member 35 suitably secured together. The tubular member provides means of attachment to the cable and means for clamping the body to the shield or housing for the spark plug. The insulating end of the body carries the spring clip and has a flange extending around it for preventing oil from running down on the clip and spark plug.

Fig. 1 is a longitudinal sectional view and 45 side elevation showing a spark plug with its shield and a cable end with a connecting device involving my invention shown in longitudinal section.

Fig. 2 is a fragmentary sectional view of a 50 modified mounting for the clip.

Fig. 3 is a longitudinal sectional view showing modifications in details.

Fig. 4 is a transverse sectional view on the line 4—4 of Fig. 3.

The spark plug may be of any suitable type 55 and provided with any suitable type of tip 6 which may be short as shown in full lines or longer as shown in dotted lines at 6'.

The shield may be formed for instance of sheet aluminum having a base or cup-like portion 7 for surrounding the lower end of the spark plug, the cylindrical body member 8 split at 8' along one side and having a conical extension 9 which is flanged over as at 9'. The whole is secured together by a cap 10 65 which may have ventilating passages 11.

Conducting portion 14 of the cable has secured to it electrically at its outer end a suitable form of clip 15 for engaging the tip 6 of the spark plug. Such cables are usually 70 provided with some form of rubber or fabric insulation 16 and a metallic armor 17 of helical interlocked type.

The terminal body consists of the tubular metallic portion 18 and the insulating portion 19 formed for instance of suitable moulded composition. These two parts can be secured together by moulding the insulating composition into a recess 20 in the metallic portion or by moulding the insulating portion 19' in advance and providing it with a screw threaded portion 20' which can be screwed into an end of the tubular portion 18' as shown in Fig. 3. The smaller end of the body member 18 is provided with a sleeve 85 portion 21 into which the armor 17 of the cable is received and anchored for instance by staking a portion 22 of the sleeve into a groove or outer surface of the armor. An eyelet 23 may be moulded into the end of the 90 insulating portion 19 and riveted over the base 24 of the clip for holding the clip in place. The end of the cable 14 may be soldered as at 25 to the outer end of the eyelet 23 in order to afford a permanent connection. 95

The eyelet however might be formed integrally with the clip 15' as shown at 23' in Fig. 2. On the other hand, the eyelet might be provided with a threaded portion 23'' screwed into the insulation 19' as shown in Fig. 3.

This figure also shows a modified form of armor or protective covering 17' and a split bushing 21' held in place by an indented or staked portion 22' and the whole held in the 5 sleeve 21 by spinning over a flange 21".

An outer end 26 of the metallic portion 18, is tapered to fit the interior taper of the conical extension 9 of the shield. An annular clamping member 27 is provided which has a 10 screw threaded engagement 28 with the tubular member 18 so that the clamping ring can be adjusted back and forth on the tubular member and brought to bear against the outside of the conical extension 9 to clamp the 15 holder in place on the shield. This ring or sleeve like member 27 may be of any suitable cross section and knurled or otherwise surfaced to facilitate its adjustment. A groove 29 provides a convenient means for threading 20 the member 18 and also space for the end 9' of the extension 9.

The insulating portion 19 is preferably largest at its outer end where it has a flange 30 with a groove 31 behind it and is tapered 25 off at 32 so that a protecting skirt is provided. Any oil which may collect on the inside wall of the shield at the base of this tapered portion of the insulating portion 19 will flow over it only as far as the adjacent edge of the 30 groove 31 from which it will drop off into the bottom 7 of the shield and thus be prevented from reaching the terminal clip 15.

It will thus be seen that the device can be readily attached to the end of a cable and 25 permanently secured thereto, also that the holder can be readily clamped on or released from a shield so that the cable has not only the mechanical connection by the clip to the tip of the spark plug but also a secure connection to the shield which is clamped by the spark plug to the engine.

It will also be seen that with this construction the same clip and holder can be mounted in a shield having a short spark 45 plug with a tip 6, or by simply turning over or rotating the tip 180 degrees the tip may be applied to a long plug having a tip 6'. In both cases the holder will be found mounted concentric to the extension 9 of the 50 shield so that it can be clamped in position as shown in Fig. 1 or upside down if necessary.

I claim:

1. An electrical connector comprising a 55 holder for the end of a cable consisting of a tubular metallic portion adapted to be clamped to a shield and an extended head formed of insulating material and having a terminal flange with a groove behind the 60 flange for preventing oil running down and a clip secured to the end of the holder for attachment to a spark plug.

2. A cable terminal comprising a tubular metallic member having a tapered portion 65 for clamping and grounding in a shield ex-

tension and having a portion adapted to be attached to the armor of a cable, an insulating head secured to one end of said metallic member and having a projecting flange and a groove adjacent thereto and a clip secured 70 to said insulating head for attachment to a spark plug tip.

3. A cable terminal comprising a tubular metallic member having a tapered portion for clamping in a shield and having a portion adapted to be attached to the armor of a cable, a tapered insulating head projecting as a continuation of the tapered portion of said metallic member and having a projecting flange and a clip secured to said insulating head for attachment to a spark plug. 75

4. A cable terminal comprising a tubular metallic member having a portion for clamping and grounding in a shield extension, a screw threaded portion adjacent thereto, and a socket portion adapted to be attached to the armor of a cable, an insulating head secured to one end of said metallic member and having a projecting flange and a groove adjacent thereto, a clip secured to said insulating head for attachment to a spark plug and a screw clamp adjustable on the threaded portion. 80 90

5. A cable terminal comprising a tubular metallic member having a shouldered portion and an adjusting member threaded on the metallic member and coacting with the shoulder portion for clamping and grounding on a shield extension, an insulating head secured to one end of said metallic member and having a projecting oil-stopping flange and a clip secured to said insulating head adjacent said flange for attachment to a spark plug tip, and an armored cable having a conductor connected to said clip and having an armor secured to the opposite end of said tubular metallic member. 95 100

6. An electric cable terminal comprising an insulated conductor having a metallic protecting armor, a tapered member on said conductor adapted to fit within a shield extension, means for mechanically connecting the armor and said tapered member to the shield extension including an adjusting nut, an insulating head on the end of the insulated conductor having a projecting oil-stopping flange and a spring terminal clip mechanically secured to said head and electrically connected to said conductor adjacent said flange. 110 115

7. A cable terminal comprising a tubular metallic member having a tapered portion for fitting inside of a shield extension and having a threaded portion adjacent thereto, a clamping nut adjustable on said threaded portion for engaging the exterior of the 120 shield extension, an insulated conductor passing through said tubular metallic member and having a metallic armor mechanically and electrically connected with said tubular metallic member and an insulating head se- 125 130

cured to said tubular metallic member and
extending from the same around the insulated
conductor and having a projecting oil-stop-
ping flange at its outer end and a spring clip
5 mechanically connected to said head and elec-
trically connected to said conductor.
